S. J. MYERS.

TIE,

APPLICATION FILED SEPT. 20, 1916.

1,258,433.

Patented Mar. 5, 1918.

UNITED STATES PATENT OFFICE.

SAMUEL J. MYERS, OF MERCER, PENNSYLVANIA, ASSIGNOR TO MERCER MANUFACTURING COMPANY, OF MERCER, PENNSYLVANIA, A CORPORATION OF PENNSYLVANIA.

TIE.

1,258,433.

Specification of Letters Patent.

Patented Mar. 5, 1918.

Application filed September 20, 1916. Serial No. 121,275.

To all whom it may concern:

Be it known that I, SAMUEL J. MYERS, a citizen of the United States, residing at Mercer, in the county of Mercer and State of Pennsylvania, have invented new and useful Improvements in Ties, of which the following is a specification.

This invention relates to a tie for securing a brick wall to a wooden structure and has for its primary object to so construct a device that a portion thereof may be readily driven into the wooden structure, without marring the remaining portion.

Besides the above my invention is distinguished in the novel manner of connecting the shank to the body portion of the tie so that the shank may be driven in the proper direction irrespective of the manner in which the device is driven by a hammer. With these and other objects in view the invention will be better understood from the following detail description taken in connection with the accompanying drawing wherein:—

Figure 1, is a perspective view of the tie. Fig. 2, is a top plan view thereof. Figs. 3 and 4, are diagrammatic views. Fig. 5, is a detail view of a modification. Referring to the drawing it will be seen that the tie is formed from a single length of wire 1, shaped to form a body 2, the extremities 3 and 4 of which being bent at an angle thereto. A shank 5 is formed as a continuation of the extremity 4, and extends at an angle thereto. The shank has its free extremity sharpened and is further provided with barbs 6, adapted to effectively hold the shank in the wooden structure.

A very important feature of my invention is the manner of forming the tie at the point of juncture between the shank and the extremity 4, so that the blows of a hammer delivered at different angles can be accommodated. At the point of juncture of the shank with the extremity 4, I have bulged the tie as indicated at 7 so that the hammer striking surface 8 will be disposed to one

side of the extremity 4 so that the hammer will not strike the extremity 4.

The outward bend of the tie at this point 50 reinforces the tie at the point of juncture between the shank and the extremity 4.

Another advantage of this bulged portion 7 is that an instrument may be inserted behind for removing the tie as shown in 55 the diagrammatic view Fig. 4.

In Fig. 5, I have shown a slight modification wherein a portion of the tie as the point of juncture between the shank 5 and the extremity 4 is bent back upon itself as 60 illustrated at 9 and as a result the shank 5 is reinforced throughout a portion of its length.

From the foregoing description taken in connection with the accompanying drawing 65 it should be apparent that I provide a device which is admirably adapted for the purpose for which it is intended, that the device is simple, durable and efficient of construction and may be manufactured and 70 sold at a comparatively low cost and further capable of being readily removed without marring to a great extent the wood work to which the device is applied, as clearly 75 illustrated in Fig. 4, of the drawing, wherein in an ordinary rod 3, is inserted behind the tie.

Having described my invention what I claim is:—

A tie for the purpose set forth, comprising a rod bent to provide parallel oppositely extending members and a right angular member connecting said extensions, one of said extensions having its end pointed and its sides barbed, the other extension 85 having its end bent at an outward angle with respect to the longitudinal axis thereof, and the connecting member for the extensions at its juncture with the barbed and pointed member being rounded outwardly 90 in the direction of the second mentioned extension.

In testimony whereof I affix my signature.
SAMUEL J. MYERS.
